UNITED STATES PATENT OFFICE.

GEORGE W. GENTRY, OF YEAGER, OKLAHOMA, ASSIGNOR OF ONE-FOURTH TO HARRY H. DIAMOND AND ONE-FOURTH TO JOHN R. DUTTON, BOTH OF HOLDENVILLE, OKLAHOMA.

WINDMILL.

Application filed June 30, 1922. Serial No. 571,916.

To all whom it may concern:

Be it known that I, GEORGE W. GENTRY, a citizen of the United States, residing at Yeager, in the county of Hughes and State 5 of Oklahoma, have invented certain new and useful Improvements in Windmills, of which the following is a specification.

This invention relates to wind wheels of the horizontal type and has for its object 10 the provision of novel means for throwing the wheel into or out of the wind. The invention also seeks to provide means for facilitating the lubrication or repairing of the wind wheel and also seeks to provide novel 15 means for utilizing the power generated by the wheel. The invention is illustrated in the accompanying drawings and will be hereinafter fully set forth.

In the drawings—

20 Figure 1 is a side elevation of a wind wheel embodying my present improvements;

Fig. 2 is a plan view of the wheel and the parts co-operating directly therewith;

25 Fig. 3 is a detail perspective view of the shield and the tail vane;

Fig. 4 is an enlarged vertical section on the line 4—4 of Fig. 1; and

Fig. 5 is a detail perspective view of a 30 bracing flange or spider provided at the upper end of the stand pipe.

In the drawings, the reference numeral 1 indicates a concrete or similar base or foundation which is laid at the point where the 35 wind wheel is to be set up. Upon this base or foundation, I erect a frame 2 supporting a platform 3 from which a stand pipe 4 rises to any desired height. The stand pipe may be secured in the platform in any convenient or preferred manner and is illustrated as fitting within a flange 5 on the platform and resting on ball bearings. A similar flange 5 is provided on the under side of the platform. Adjacent the upper 40 extremity of the stand pipe, I provide a flange or spider 6, from the edge of which lugs 7 depend and in the said lugs I secure the upper ends of guy wires 8 which diverge downwardly and have their lower ends secured to stakes or other anchors 9 in the ground. As indicated at 10, turnbuckles 50 may be interposed in the guy wires so that the proper tension may be placed upon the wires to hold the stand pipe against all vertical oscillation. At intervals in the height 55

of the stand pipe, I secure thereto the steps 11 to permit a workman to readily reach the top of the stand pipe when lubrication, adjustment or repairing of the wheel or the parts co-operating directly therewith may 60 be needed. The uppermost step 12 is made somewhat larger than the lower steps and is reinforced by a brace 13 extending therefrom to the stand pipe so that the workman may stand upon the upper step while performing the necessary work. All the steps are provided with split collars 14 which are secured firmly about the stand pipe by bolts, indicated at 15, inserted through their split portions. The brace terminates in such a 70 split collar and an extra step 13' projects from said collar at the opposite side of the stand pipe so that a firm footing for the workman will be provided. It will also be noted that the uppermost step 11 below the 75 brace 13 is close to the brace, this arrangement being a pronounced convenience in actual practice.

Above the spider or flange 6, the stand pipe 4 is reduced to provide an annular 80 shoulder or bearing 16 upon which is supported a turntable 17 having a vertically disposed hub 18 which encircles the stand pipe, as shown most clearly in Fig. 4. The bearing provided by the shoulder 16 may be 85 a plain bearing, or it may be equipped with balls or other anti-friction devices as may be preferred, and it is to be understood that throughout the entire mechanism all bearings may be plain or anti-friction as may 90 be desired. Secured to the turntable and projecting radially therefrom is the lower arm 19 of a shield-carrying frame, the outer end of said arm 19 being connected by a vertical bridge member 20 with the outer 95 end of the upper arm 21 which is similar in all respects to the said arm 19. The upper arm 21 is secured to the upper side of a frame 22 which is arranged at a right angle to the arms 19 and 21 and has its lower side secured upon the turntable 17, as clearly shown in Fig. 3. The lower side of this frame is split or divided to accommodate the hub of the turntable, as shown at 23, and the frame may conveniently be 100 formed from a flat bar or metallic strap having its upper and lower sides connected by vertically disposed end portions 24. To one end portion 24 of the frame 22 and to the vertical end member 20, I secure the 105 110

shield 25 which consists of a plate of sheet metal or other material having an arcuate form and having its upper and lower edges diverging inwardly, as shown at 26, where-
5 by the wind currents striking the shield will not only be prevented from acting di- rectly upon the vanes of the wind wheel but will also be deflected upwardly and down- wardly so that they will be caused to flow
10 above and below the wheel without affecting the movement of the same. It will be readi- ly noted from an inspection of the drawings that the members 24 and 20 are located at or very near the ends of the shield so that
15 the shield defines an arc of about ninety degrees and, therefore, encircles one-fourth of the wind wheel. The upper bar 21 ex- tends somewhat beyond the upper bar of the frame 22, as shown at 27, and upon this
20 projecting extremity of the said bar 21 I pivotally attach the upper tail vane arm 28, the lower tail vane arm 29 being pivotally attached to the turntable in vertical aline- ment with the pivot of the arm 28. The
25 arms 28 and 29 extend outwardly a distance approximately equal to one-half the length of the frame 22 and to the outer portions of the said arms, I secure the tail vane 30 which will preferably be of sheet metal but
30 may be of other material and may be of any preferred design which will present a suffi- cient area to the wind to effect the shifting of the vane. Extending from the pivot 31 of the lower arm 29 is a counterbalance
35 arm 32 which is preferably integral with the arm 29 but may be otherwise united there- with. This arm 32 carries a counterbalance 33 upon its free end and a trip rope 34 is secured to the arm and extends therefrom to a guide
40 pulley 35 on the under side of the frame 22 adjacent the edge of the shield 25 and thence passes downwardly to a point near the ground whereby it may be readily manipu- lated. To the arm 29 adjacent the inner end
45 of the vane 30, I secure a trip rope 36 which passes therefrom to a guide pulley 37 at the opposite end of the frame 22 and thence de- pends to a point near the ground, as will be readily understood. An extension coiled
50 spring 38 has one end attached to the upper edge of the shield 25 and its other end con- nected to the upper vane arm 28 and is so arranged that it will be constantly under tension and in one position of the vane will
55 be disposed at one side of the pivot thereof, while in another position of the vane will be at the opposite side of the pivot, as will be readily understood upon reference to the full and dotted lines in Fig. 2, so that the spring tends to hold the vane in the position in
60 which it may be set.
65 The drive shaft 39 extends through the stand pipe 4 and is rotatable therein, the lower end of the shaft projecting below the lower flange 5 and being equipped with a
beveled gear 40, while the upper end of the shaft projects above the upper end of the stand pipe and has the hub 41 of the wind wheel secured rigidly thereto, the upper ex- tremity of the shaft fitting in the bar 21 and frame 22 at the junction of the same. The hub may be secured to the shaft in any desired or preferred manner and I have illustrated a bolt 42 inserted diametrically through the shaft and the hub. Extending
70 from the hub 41 near the upper and lower ends thereof are flanges or disks 43 to which the wind wheel vanes or blades 44 are rigidly secured, and it is to be understood that any desired number of these blades may be pro-
75 vided as may seem desirable or prove most efficient, and while I have illustrated six blades in the accompanying drawings, a greater or less number may be employed. The blades are preferably of sheet metal so
80 as to possess the requisite strength and dura- bility without excessive weight and the upper and lower edges of the several blades are turned inwardly, as indicated at 45, where-
85 by a concave surface will be presented to the wind. Brace rods 46 are secured to and ex-
90 tend between the several blades so as to reinforce the structure and to prevent col-
95 lapsed of the blades under very strong winds. Upon reference to the arrows in Fig. 2
100 which indicate the direction of the wind, it will be seen that the wind will strike directly upon the concave faces of the several blades and the impact and pressure of the wind upon the blades will cause them to swing
105 around the stand pipe as a center and there-
110 by impart rotation to the shaft 39. The rotation of the shaft 39 will, of course, be transmitted directly to the beveled gear 40 and utilized to drive various machinery. In the accompanying drawings, I have shown the beveled gear 40 meshing with a gear 47 which is disposed within the frame 2 and secured upon a shaft 48 extending through the frame and beyond the sides of the same.
115 At one end, this shaft 48 is equipped with a pulley 49 adapted to receive a bolt which may be carried to any desired point to drive a threshing machine or other machinery.
120 At the end remote from the pulley 49, the shaft 48 is equipped with a crank 50 which is connected by a pitman 51 with the piston rod 52 of a pump. I also show a gear 53 carried by a shaft disposed at a right angle to the shaft 48 and adapted to mesh with the gear 47 so that power may be transmitted through the gear 53 and the shaft carrying the same to any desired point. It will be
125 understood that another shaft may be ar- ranged in axial alinement with the shaft carrying the gear 53 and at the opposite side of the shaft 48, but I have not illustrated the same. It will also be understood that the gears 47 and 53 may be slidably mounted upon their respective shafts and controlled
130

by shifting levers so that they may be thrown into or out of operative position at will.

As has been stated and as will be readily understood upon reference to Fig. 2, the wind wheel is rotated by the force of air striking against the blades or vanes 44. The vane 30 is disposed parallel with the direction of flow of the wind and in the position shown in Fig. 2 will hold the shield 25 in the face of the wind so that only one-half of the blades will be presented to the wind and the resistance to the rotation of the wheel which would be caused by the wind striking the convex side of the remaining blades is overcome. When the wheel is to be thrown out of gear, the trip rope 34 is drawn downwardly so that the arms 32 and 39 will be swung about the pivot 31, the arm 28, of course, following the movement. The tail vane will thus be brought into the position shown in dotted lines in Fig. 2 which is substantially alined with the central radius of the shield 25 and the wind striking upon the vane will then cause the turntable 17 with all the parts mounted thereon to swing around the stand pipe and bring the shield 25 directly into the face of the wind so that none of the blades will be presented to the wind sufficiently to effect rotation of the wheel. When it is desired to again bring the wheel into operation, the trip rope 36 is drawn downwardly thereby swinging the vane to the position shown in full lines in Fig. 2, whereupon the wind striking upon the vane will return it relatively to the position shown in dotted lines carrying with it the shield 25 so that the blades 44 will be again exposed to the force of the wind and the wheel will be rotated. The arm 32 and the weight 33 counterbalances the tail vane and the shield so that the movement of the devices in shifting into and out of the wheel will be easy and even.

My improved apparatus is simple in construction and arrangement and may be manufactured and set up for use at a cost which is not prohibitive and will be found highly efficient in operation.

Having thus described the invention, what is claimed as new is:

1. In an apparatus of the character described, the combination of a frame, a platform supported by the frame, a stand pipe rising from the platform, a flange at the upper end of the stand pipe having depending lugs, guy wires having their upper ends se-

cured to said lugs and their lower ends anchored, a drive shaft rotatably mounted in the stand pipe, a horizontally disposed wind wheel secured to the upper extremity of the shaft, and means within the supporting frame for transmitting motion from the lower end of the shaft.

2. In an apparatus of the character described, the combination of a vertically disposed shaft, a horizontally disposed wind wheel secured to the upper end of said shaft, a shield mounted concentrically with the shaft and adapted to turn about the same, said shield being of arcuate formation and concentric with and disposed beyond the wheel, a vane pivotally mounted eccentrically to the shaft and adapted to swing about the shaft with the shield, means for turning the vane about its pivotal support in either direction, and yieldable means for holding the vane in a set position relative to the shield.

3. In an apparatus of the character described, the combination of a support, a turntable mounted upon the support concentric therewith, a shaft extending through and rotatable in the support, a wind wheel carried by the upper end of the shaft, an arcuate shield supported by the turntable and disposed radially beyond the wheel, a vane mounted eccentrically upon the turntable, means for turning the vane pivotally in either direction, and a tension spring connected with the vane and with the shield at points out of alinement with the pivot of the vane.

4. In an apparatus of the character described, the combination of a support, a shaft extending through the support and rotatable therein, a horizontally disposed wind wheel carried by the upper end of the said shaft, a turntable mounted upon the support concentric therewith, a shield carried by the turntable and disposed radially beyond the wheel, a vane pivotally mounted upon the turntable eccentric to the wind wheel and the shield and connected with the shield, a counterbalance arm rigid with the vane, a trip rope secured to the counterbalance arm and extending to the ground, another trip rope secured to the vane and extending therefrom to the ground in opposition to the first-mentioned trip rope, and a coiled spring having its ends attached respectively to the vane and to the shield at points out of alinement with the pivot of the vane.

In testimony whereof I affix my signature.
GEORGE W. GENTRY. [L.S.]
